CLAIM

The ornamental design for a sample holder for ionized sample analysis, as shown and described.

DESCRIPTION

FIG. 1 is a front view of a sample holder for ionized sample analysis of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof;

FIG. 8 is an enlarged view showing a portion of FIG. 1 defined by lines 8-8 and 8'-8';

FIG. 9 is an enlarged view showing a portion of FIG. 4 defined by line 9-9;

FIG. 10 is an enlarged view showing a portion of FIG. 7 defined by lines 10-10 and 10'-10';

FIG. 11 is an enlarged cross-sectional view along the line 11-11 in FIG. 9, in the area designated by 11'-11' in FIG. 8;

FIG. 12 is an enlarged cross-sectional view along the line 12-12 in FIG. 9, in the area designated by 12'-12' in FIG. 8;

FIG. 13 is an enlarged cross-sectional view along the line 13-13 in FIG. 9, in the area designated by 13'-13' in FIG. 8; and,

FIG. 14 is an enlarged cross-sectional view along the line 14-14 in FIG. 9, in the area designated by 14'-14' in FIG. 8.

The features shown in evenly-dashed broken lines depict portions of the sample holder for ionized sample analysis that form no part of the claimed design. The dot-dash-dot broken lines depict the boundaries of the claim and form no part thereof. The dash-dot-dot-dash broken lines depict indicators for sectional views and enlarged views and depict

boundaries in the enlarged sectional views and enlarged views, the dash-dot-dot-dash broken lines form no part of the claimed design.
